18 Claims. (Cl. 62—31)

This invention relates to improvements in methods and means for refrigerating by use of solid refrigerants, such as water ice (solid H_2O), and carbon dioxide ice (solid CO_2).

5 A principal object of the invention is to provide a method of refrigerating by means of solid refrigerants that shall be more efficient than the prior methods and shall permit of close regulation of the effective refrigerating temperatures.

10 Another object of the invention is to provide a method of refrigerating by means of solid refrigerants whereby the effective refrigerating temperatures are to a substantial degree independent of the volume of the refrigerant, and to this latter end, the invention contemplates the provision of 15 a method for materially increasing the refrigerating efficiency of relatively small quantities of a solid refrigerant.

More specifically, an important object of the 20 invention is the provision of a method of refrigeration by the use of a solid refrigerant which will produce effective refrigerating temperatures in the refrigerating chamber more closely approximating the melting or subliming temperature of 25 the ice than the heretofore known methods, and which will maintain such temperatures even when the mass of ice has been reduced to relatively small dimensions.

Still another object of the invention is the 30 provision of a method of refrigerating by use of solid refrigerants which will permit a rapid acceleration in the rate of ice melting or sublimation irrespective of the volume of the refrigerant when the temperatures in the refrigerated area are increased.

A still further object of the invention is to provide a method of refrigeration by means of a solid refrigerant which will permit the refrigeration of 35 practically any desired space whether occupied 40 with a gas (including air), liquid, solid or a combination thereof without actual contact of the refrigerant with the contents of the space whereby when required, the refrigerant may be entirely divorced from the refrigerated area.

45 A still further object of the invention is the provision of refrigerating apparatus for use with a solid refrigerant in which the principal heat transfer to the refrigerant takes place from the refrigerated space or mass to a conductor of high thermal conductivity and extended surface, and thence conductively to a relatively small surface of the refrigerant through a section of the conductor sufficiently large to transmit the required amount of heat for maintaining a predetermined 50 effective refrigerating temperature.

The invention further contemplates the provision of refrigerating apparatus for use interchangeably with solid CO_2 , solid H_2O or other solid refrigerant, in which the principal heat transfer to the solid refrigerant takes place from the refrigerated area or mass to a conductor of high thermal conductivity and extended surface, thence conductively to a relatively small surface of the refrigerant through a section of the conductor of sufficient size to transmit an amount 5 10 of heat required for maintaining a predetermined effective refrigerating temperature and in which differences in the melting or subliming temperatures of the different refrigerants may be compensated by means of variable conductor resist- 15 ances placed between the conductor and the refrigerant.

Still more specifically, as regards the use of solid H_2O and similar solid refrigerants of relatively high melting point, an object of the invention is to provide a novel method of refrigeration which will produce effective refrigerating temperatures more closely approximating the melting temperature of the ice than has heretofore been possible, and will maintain such temperatures 20 even after the volume of the ice has been reduced to relatively small amounts.

Again specifically, and as regards the use of solid refrigerants, such as solid CO_2 , having a relatively low melting point or point of sublimation, another object of the invention is to provide a method of refrigerating with such refrigerants which shall be both highly efficient and capable of close and accurate regulation of the effective refrigerating temperatures, said temperatures being maintainable even when the volume of the refrigerant has been reduced to relatively small amounts.

A further and more specific object of the invention is the provision of a method of refrigeration 30 by the use of carbon-dioxide "ice" or the like which will permit the automatic maintenance of an approximately constant temperature in the refrigerating chamber under varying conditions of outside atmospheric temperature, of content of refrigerating chamber, and of "ice" supply.

A further object of the invention is the provision of refrigerating apparatus for use with CO_2 , "ice" or the like in which the principal heat transfer from the refrigerating chamber and its 40 contents to the "ice" takes place convectively from the chamber to a conductor of high thermal conductivity, thence conductively to the "ice", and in which means may be provided for regulating the convection currents in such a manner 45 50 55

that an approximately constant temperature may be maintained in the refrigerating chamber.

A further object of the invention is to provide a method of and apparatus for refrigerating by the use of CO₂ "ice" or the like whereby an initial rapid chilling of the refrigerating chamber or the contents may be had when desirable by a comparatively rapid melting or sublimation of the "ice", and thereafter the required temperature 10 maintained by a much slower sublimation of the "ice" store.

A further object of the invention is the production of a refrigerating unit of such character that it may be employed either in household and 15 stationary refrigerators or in the refrigeration of railway cars, motor truck bodies, or other transportation units.

Still another object of the invention is to provide simple and relatively inexpensive refrigerating units of a character adapted for use in household and other refrigerators employing solid H₂O whereby my invention may be readily available 20 for that class of refrigeration.

A still further object of the invention is the provision of a refrigerating apparatus in which 25 heat may be absorbed from an upper portion of the space to be cooled and conducted downwardly through an all-metallic path of heat transfer to a solid refrigerant positioned at a lower level. 30 The invention further resides in certain novel and advantageous structural features and details and in specific embodiments representing various applications thereof to different classes of refrigeration, all as hereinafter set forth and illustrated 35 in the attached drawings, in which:

Fig. 34 is a vertical sectional view through a further modification of the invention in which the extended heat-absorbing surfaces extend around at least a portion of the upper part of 50 the space to be refrigerated, and

Fig. 35 is a horizontal sectional view of the form of refrigerator shown in Fig. 34.

Water ice or solid H₂O is more widely used than any other form of refrigerant. One of 55 the principal drawbacks in the prior methods of using this refrigerant or, in fact, any solid refrigerant is that although any given mass of the refrigerant, no matter how small, has a fixed refrigerating value; yet the smaller the mass becomes, the slower its refrigerating action becomes also. This is due to the fact that the heat is usually either entirely or almost entirely brought to the ice convectively either by air or a liquid, and the amount of heat taken up by the refrigerant, other things being equal, depends directly on the amount of the effective surface contact between the refrigerant and the circulating fluid. Obviously as the ice melts, the surface area becomes less and the refrigerating action slower. 60 In the construction of refrigerating apparatus, this feature, heretofore, has been given no consideration, and no effort has been made to compensate for the rapid decrease in efficiency as the refrigerant loses volume and surface area. As a 70 75

result, a great deal of ice is constantly being used with very indifferent or inferior results.

One reason that the mechanical household refrigerator has progressed so rapidly is because the ordinary water ice refrigerator cannot maintain satisfactory refrigeration unless it is continually serviced and kept practically full of ice at all times. For the same reason, a large and growing field for refrigeration of foodstuffs in motor transportation has avoided the use of water ice and other solid refrigerants. Practically the only method attempted to improve the efficiency of water ice as a refrigerant has been the use of salt, a method of limited application which apparently cannot be greatly extended.

I have discovered that the principal obstacles to the efficient use of water ice and other solid refrigerants can be largely overcome if the heat from the space or material to be refrigerated is picked up by comparatively extended surfaces of a metal heat conductor, such as copper, aluminum or iron, and transferred through a substantial cross section of the metal conductor directly to a surface of the body of ice with which the metal conductor is either in immediate contact or in suitable conductive relation. I have found that by this method, the ice can be melted at practically a constant rate, thus providing a constant effective refrigerating temperature practically independent of the volume of the refrigerant, and even with extremely small masses of the latter. I have found also that the refrigerant can be melted at an almost inconceivable rate when large amounts of heat are passed over the extended metal surfaces. With a sufficient cross section of the conductor metal, as small as thirty square inches of contact surface with the refrigerant is sufficient to melt enough water ice to keep a good household refrigerator below 50° F. even on the top shelf in the warmest weather; and after the doors have been opened as long as three minutes, this refrigerator will return to its original low temperature within twenty minutes or one-half hour. It is essential in the practice of my invention that the solid refrigerant be maintained in conductive relation with a substantial metal conductor having a suitably extended surface area in the refrigerated space.

While the invention is of great importance in conjunction with the use of water ice, it is also of great value in the use of all other solid refrigerants, such as solid carbon dioxide and frozen brine. The apparatus embodying my invention need vary only slightly to meet the requirements of the particular kind of refrigerant and the type of refrigeration required. If, for example, refrigerating temperatures around 35° to 45° F. are desired and water ice is to be used by reason of its cheapness and availability, then a relatively large amount of extended conductor or fin surface will be required because of the small temperature differential between the water ice and the temperature required; while the same temperature can be secured by use of solid carbon dioxide with considerably less surface area by reason of the fact that with solid carbon dioxide the conductor can be chilled to almost any temperature required down to say minus 50° F., and accordingly a relatively large temperature differential be maintained between the conductor and the refrigerated space. Obviously if temperatures are wanted near or below the melting point of water ice, then some other solid refrigerant may be used with a sufficiently low melting or subliming point that the conductor can be put

at a temperature affording the differential required to maintain the refrigeration wanted. Frozen brine may be used especially when put up in small and easily handled units in liquid-tight metal containers. The heat transferred from the conductor to the solid brine through the metal container, however, is not as constant and controllable as in the direct contact of water ice with the conductor or the contact of carbon dioxide ice with the conductor through a known amount of conducting resistance, as hereinafter more specifically set forth. However, as the frozen brine can be provided with a melting point practically anywhere between 32° F. and considerably below zero and has now come into more common use and also is comparatively cheap, it is apparent that it will have a limited use as a solid refrigerant means in my method of refrigeration. Of course, frozen brine directly in solid state can be used in the same way as water ice or carbon dioxide ice by permitting the melted brine to drain off.

It will be understood that for maximum control of refrigeration, with this type of refrigerant it is desirable to limit so far as feasible transfer of heat from the refrigerated space or mass to that passing through the conductor. This can be accomplished by providing adequate insulation preventing transfer by radiation or by other than conduction through the selected conductor. By thus establishing a principal and practically sole path of transfer and utilizing in conjunction therewith suitable known resistances, a substantially perfect control may be obtained. This method of control also affords a simple method for providing apparatus suitable for use with refrigerants such as water ice and carbon dioxide ice having widely different melting points. Thus a single refrigerating apparatus can be built that can use as a refrigerant either carbon dioxide or water ice or frozen brine, or, in fact, any solid refrigerant, and that can maintain practically any required temperature under constant outside temperature conditions within the limits of the particular refrigerant used by a simple manipulation of a conductor resistance interposed between the conductor and the refrigerant, and by providing in the same apparatus either manually or thermostatically-operated means to regulate the convection currents from the extended conductor surfaces or fins, the required temperature can be maintained irrespective of normal outside temperature variations.

With reference to the drawings, in which I have illustrated various specific applications of my invention to different types and classes of refrigeration, and with particular reference to Fig. 1, the reference numeral 1 indicates an outer shell or case of a household refrigerator of well-known type and having a compartment 3 in one of the upper corners for reception of the refrigerant. In accordance with the prior practice, refrigeration is obtained in this type of refrigerator by the convective action of air currents circulating in the space 5 to be cooled, as indicated by the arrows. The bottom of the compartment 3 and the side wall thereof exposed to the convection currents in the space 5 is formed of a metal casting 38, preferably of aluminum and its thickness, with respect to the conductivity of the metal from which it is formed, is such that heat will be conducted thereby to the refrigerant which is supported by the bottom and in heat conductive relation thereto, at

- a rate sufficient to maintain the casting at a temperature sufficiently low to provide an effective refrigerating temperature in the space 5 to be cooled, even when the refrigerant has been reduced to an exceedingly small volume, whereby it is possible to maintain adequate refrigerating temperatures with relatively infrequent services.
- The vertical side wall of the compartment 3 provides an extended surface for absorbing heat from the space to be cooled, and in order further to extend said surface it may be provided with fins 39 of a good heat-conducting metal, such as copper.
- 15 The ice-supporting bottom of the casting 38 is inclined slightly towards the juncture with the upright wall, and in the angle outlets 41 are provided for elimination of the products of evaporation or sublimation.
- 20 The principal heat transfer in this embodiment of the invention takes place through the thin metallic fins 39, down the upright side of the casting to the bottom, or ice-supporting wall. In order to regulate the amount of heat conducted from the bottom wall to the solid refrigerant, a conductor resistance in the form of sheets 42 of a heat-insulating character may be interposed between the refrigerant and the bottom wall upon which it is supported. The conductor resistance is of a predetermined value and selected to maintain a predetermined effective refrigerating temperature in the space 5. The solid refrigerant may be surrounded at its top and sides with insulation 43.
- 25 In Figs. 2 and 3, I have illustrated my invention as applied to a water cooler employing solid carbon dioxide as the refrigerating medium. In this instance, the conductor forming an essential part of the device consists of a solid aluminum or copper receptacle 55 which is embedded in solid insulation 56. A chamber 57 is provided in the insulation 56 for the water or other liquid to be cooled. This chamber, as shown in Fig. 3, extends completely around the 30 sides of the receptacle 55, but is spaced a sufficient distance from the said conductor to maintain a desired temperature of the liquid for any predetermined temperature of the conductor. This temperature in turn is controlled by the 35 thickness of a conductor resistance 58 interposed between the solid carbon dioxide ice and the bottom wall of the conductor. With an arrangement of this character, I have found it possible to maintain substantially any desired 40 temperature of the liquid within the container 57 by simple variation of the thickness of the conductor resistance 58 which modifies the conductive relation between the conductor 55 and the refrigerant. It will be noted that in this 45 instance the conductor while having the necessary extended surface is not provided with fins, and that further the surfaces of the conductor are not in direct contact with the liquid to be cooled, but are in conductive relation therewith through 50 the insulation separating the walls of the liquid container from the said conductor.
- 55 Fig. 4 shows a similarly constructed water cooler with the addition of a storage space 60 located below the bottom of the conductor, it 55 being possible to maintain this space at practically any required temperature by variation in the thickness of the insulating member 70 which constitutes conductor resistance between the space and the bottom of the conductor 55.
- 60 75 A more or less similar form of conductor is

shown in Figs. 5 and 6, which shows a cabinet suitable for use with solid carbon dioxide for storing ice cream, frozen foods or the like. In this instance, the conductor consists of a solid aluminum casting 62, this casting comprising a base 63 and four cylindrical vertical containers 64. In this instance, the walls of the portions 64 constitute the necessary extended surface area, provisions being made for supporting the refrigerant upon the base between the said portions 64, 10 as shown in Fig. 5. For this purpose, the refrigerant may be supported within a vertical metallic or other container open at the bottom to permit the ice to come into conductive relation with the base portion 63 of the conductor, from which it 15 may be separated by a suitable conductor resistance member 65 selected to afford a desired temperature within the receptacle 64 in which the refrigerated material is stored. The entire conductor casting is surrounded by a suitable insulating casing 66, and provision is made in the form of removable cover plates 67 for affording access to the interior of the container 64.

In Figs. 7 and 8, I have illustrated a similar type of refrigerating apparatus which in addition includes storage chambers or receptacles 67 embedded in the insulating casing 66 in suitably spaced relation to the sides of the container 64, these compartments 67 being readily kept at a non-freezing temperature and being suitable for holding water or other substances or materials at a relatively low but non-freezing temperature.

In Figs. 9 and 10, I show a form of refrigerating storage box convenient for use on store counters and under similar conditions. In this instance, the storage space is surrounded on three sides and the bottom by the conductor 85, and the heat is picked up as it comes through the walls of the storage box and also from the contents and is conducted to the bottom of the conductor, and thence to the refrigerant shown as blocks of solid carbon dioxide, which is separated from the conductor by the conductor resistance 86 generally used with this refrigerant. It will be noted that the chamber which holds the refrigerant is separated from the storage chambers 87, 88, by insulation 89, and by varying the thickness or character of this insulation, this type of refrigerator can be used for a wide variety of temperatures extending downwardly considerably below zero.

Figs. 11 and 12 illustrate a one-compartment ice cream or frozen storage cabinet in which the metal conductor made of copper or aluminum takes the form of a rectangular receptacle 91 55 surrounded by suitable insulation 92. In this instance, the CO₂ ice or other refrigerant is placed on the base of the conductor with the usual interposed conductor resistance 93 and heat absorbed from the compartment conducted 60 downwardly thereto by the metal of the receptacle 91. A small removable shelf 94 is placed over the ice to support the ice cream can or other materials to be stored. A vent 95 affords escape of the sublimed gases or meltage.

In each of the refrigerating devices shown in Figs. 2 to 12, inclusive, heat will be absorbed by the extended heat-absorbing surfaces from the chamber or spaces to be cooled and conducted downwardly to that portion of the metal plate 70 which supports, and is maintained in heat-conductive relation with the solid refrigerant.

In the embodiment shown in Fig. 13, a small storage box adapted for use primarily with CO₂ ice is shown. In this instance, the conductor takes 75

the form of a rectangular container 98 which is open at one side, and provision is made for placing the refrigerant on the top wall of the conductor as illustrated, the usual conductor resistance 97 being provided. Access to the refrigerating chamber is afforded through a removable cover 98 in the insulating casing 99, and access to the refrigerating chamber is provided by a suitable removable cover member (not shown) located in the side of the said casing.

Fig. 14 shows still another form of small storage box in which the conductor 101 is in the form of a removable storage bin, this conductor being made preferably of copper or aluminum. Access 15 to the storage space is afforded through a removable cover 102 in the top of the insulating casing 103, and this top portion 104 of the casing is also hinged at 105 to permit the entire top to be turned back to permit removal of the conductor 20 101. The refrigerant in this instance is supported upon a shelf 106 which is movable within the casing and which has legs 107 which project through openings in the bottom of the casing and rest upon the floor or other supporting surface. As the CO₂ ice sublimes, the entire casing 25 settles downwardly around the shelf 106, whereby the refrigerant is maintained in continuous conductive relation with the bottom of the conductor 101. The usual conductor resistance 108 30 is interposed between the refrigerant and the bottom of the conductor.

In Figs. 15 and 16, I have illustrated a large table or cabinet type of refrigerator adapted for use either with CO₂ ice or water ice and in 35 which provision is made for obtaining in the three separate compartments three different temperatures, when CO₂ ice is used, or of two temperatures when water ice is employed. This refrigerator consists of an outer insulated casing 40 111 having in the top a chamber for a refrigerator, the opposite sides and the bottom of which are constituted by a conductor 112. The side walls of this conductor are provided with outwardly projecting fins 113, and the bottom 45 wall is slightly elevated towards the center to create a tendency of the solid refrigerant to move by gravity towards the vertical fin walls. Access to this refrigerating chamber is had through a removable cover 114. Three refrigerating chambers are provided numbered 115, 116 50 and 117, respectively, the chamber 116 being located directly below the refrigerant chamber. Baffles 118 in the chambers 115 and 117 extend vertically and preferably in contact with the outer edges of the fins 113 whereby a convective circulation is set up in which the air moves downwardly between the fins and against the side walls of the conductor. The chamber 116 is separated from the other chambers by insulating 55 walls 119, and in one or both of the chambers 115 a valve 120, which may be operated manually or automatically from a suitable thermostatic actuator, is provided for controlling the movement of the convection currents downwardly past the walls and fins of the conductor. Where carbon dioxide ice is used, the refrigerant 60 is surrounded in the refrigerating chamber on four sides and the top by suitable insulation 121, while the ice is separated from the bottom of the conductor by means of suitable conductor resistance 122. The temperature in the chamber 116 is controlled by the thickness and character 65 of the conductor resistance, whereas the temperatures in the compartments 115 and 117 are controlled not only by the conductor resistance, 70

but also by the thickness and character of the insulation 121, and may be still further controlled by manipulation of the valve 120.

Figs. 17 and 18 illustrate a small shipping refrigerator box in which the conductor 126, which 5 may suitably be made of copper or aluminum, in effect lines the four walls and bottom of the casing 127. This form of refrigerator is particularly suited for use with CO₂ ice, and it will be noted that the usual protective insulation 128 10 and conductor resistance 129 are provided.

Referring to Figs. 19 and 20, numeral 140 designates a refrigerating chamber having access doors 141 in the upper wall 142 thereof. The chamber walls are, of course, insulated in any 15 usual or preferred manner and the upper wall 142 has formed therein an opening 143. Extending into the refrigerating chamber through this opening is an insulated cabinet 144 approximately gas tight having an open top closed by an 20 access door 145. The bottom wall 144a of this cabinet has imposed thereon a conductor plate 146 which may be conveniently constructed from copper, aluminum or some other metal having a suitably high factor of thermal conductivity. 25 The edges of this plate project through the cabinet walls and are provided with vertically-extending vanes 147 projecting upwardly along the side walls of the cabinet and preferably constructed integrally with the plate 146. These 30 vanes may have either a plane surface or be transversely or longitudinally corrugated, the latter constructions providing an increased surface for contact with convection currents.

Opposing the outer edges of the vanes are 35 insulated walls 148 which combine with the cabinet to provide channels 149 through which convection currents may pass. The lower ends of these channels are closed by valves 150 regulated through a thermostat 151. In the present instance, the valves are illustrated as pivotally connected to the lower wall of the cabinet at 40 152 and connected to the movable element 153 of the thermostat by a linkage generally designated at 154.

From the interior of the cabinet a vent tube 155 may be led through the wall of the refrigerating chamber 140. This vent tube is made of metal of a high thermal conductivity, preferably copper, and includes a coil 155a disposed 50 in chamber 140 for contact with the convection currents of the chamber, preferably near the top of the chamber and where warm "pockets" are liable to occur. The outlet of the vent tube is placed below the inlet in order to induce a ready 55 flow of CO₂ gas by syphoning, and is preferably equipped with a suitable regulating valve.

The interior of the cabinet is preferably subdivided into a plurality of sections by vertically extending partitions 159 which may be constructed of insulating material. These partitions are in the present instance illustrated as two in number so that three "ice" spaces are formed. The bottoms of these "ice" spaces are formed by the plate 146 and upon the plate in 60 the bottom of each "ice" space insulation 160 may be disposed between the "ice" and the plate, the thickness of this insulation varying in accordance with the conditions under which the refrigerator is to be employed. Insulation 65 160, the thickness of which may be varied, is removable and it will be obvious that if two of the compartments have in the bottoms thereof insulation 160 of a considerable thickness while the third compartment has no insulation as sug- 70 75

gested in Figs. 19 and 20, or a relatively thin insulation as suggested in Fig. 24, the "ice" of this latter compartment will be sublimed more rapidly than that in the remaining compartments so 5 that the "ice" of this compartment acts as an initial chilling supply while that of the remaining compartments acts as a reserve supply. Thus the first mentioned "ice" supply serves to rapidly reduce the temperature of the chamber 10 when initially placed in operation or when a rapid reduction of temperature therein is necessary following an opening of the access doors 141.

If, for example, goods are placed in the 15 refrigerator at their normal temperature and must be rapidly chilled, the insulation 160 may be completely removed from one of the compartments so that the "ice" in this compartment will act very rapidly to reduce the temperature of 20 the chamber and to chill the goods to the desired point. The desired temperature having been attained, the "ice" in the remaining compartments is held in reserve to maintain this temperature thus materially increasing the 25 period over which refrigeration is possible and particularly adapting the apparatus for use in transportation of perishable goods where facilities for replenishing the "ice" store are poor.

When pre-cooled products are placed in the 30 refrigerating chamber, then the bottoms of all of the compartments may be provided with insulation thus providing a maximum period of refrigeration for a given "ice" supply. By varying the extent to which the bottoms of the 35 compartments are insulated from conductor plate 146 a limited control of the rate of melting of the "ice" may be obtained and thereby a limited control of the temperature of the storage chamber and contents secured.

40 A drip pan 161 is preferably disposed beneath the cabinet for the reception of water resulting from the defrosting of vanes 147 and the storage spaces of the refrigerating chamber are preferably separated from the cabinet spaces by 45 foraminous screens 162.

The principal amount of the heat used in melting, or subliming the "ice" is transferred by convection from the storage chamber and its 50 contents to the vertically extending vanes 147, thence conductively to the plate 146, thence conductively directly, or through insulation 160 to the "ice". A smaller amount of heat is transferred by conduction through the insulations of 55 the "ice" cabinet and walls 148, and by internal convection currents within the "ice" cabinet and the space surrounding the vanes 147. Control of the temperature of the storage chamber and 60 contents is secured in part by varying the size and character of the conductor plate 146 and vanes 147, and of the insulations 144, 144a and 148 and the insulated chamber walls and doors. However, actual changes in temperature in the 65 contents of the storage chamber during reduction to a desired level, as well as climatic and artificial changes in temperature outside the storage chamber may require a further means for securing a constant temperature inside the chamber. This is achieved by the thermostatic 70 or manual control of the convection currents through channels 149 and transferring more or less heat to conduction vanes 147 and plate 146. By these several means a variation of the rate of subliming or melting of the carbon-dioxide 75 "ice" of as much as 1,000% can be attained

which I believe is sufficient to accomplish the objects of this invention.

The structure of Figs. 21 and 22 is substantially identical with that of Figs. 19 and 20, with the exception of the fact that the chamber 140 5 has its access door 141a mounted in the side wall thereof and that communication between the channels 148 and the storage space in the upper ends of these channels instead of being made only through openings 163, formed in the insulating walls, includes one or more ducts 164 opening at the inner end through the wall of channel 149 and having the outer end disposed adjacent to the wall of the chamber 140 or where warm pockets are likely to occur. A further slight modification of the control of the channel is employed in that the valves 150a instead of being supported by the cabinet, as in Figs. 19 and 20, are directly supported from and secured to the movable member 153 of the thermostat. The thermostat has further associated therewith baffle shields 165 which prevent chilled air, descending from the convection channels, from directly contacting thermostat 151 and thus causing too early a closing operation of the valves 150a.

The form shown in Figs. 23 and 24 is identical with the structure of Figs. 21 and 22, with the exception of the fact that conduction vanes are 30 provided entirely about the cabinet walls and entrance to the convection channels is largely through ducts 164a, the intake ends of which are disposed adjacent to the vertical walls of the chamber 140.

In Figs. 25, 26 and 27, I have illustrated refrigeration apparatus particularly adapted for household uses and embodying means for producing water ice cubes and for storing frozen products. From an inspection of Fig. 27, it will 40 be noted that the conductor plate 146, which forms the false bottom of the cabinet, instead of being in direct contact with the insulating bottom 144a thereof is in vertical spaced relation thereto, with the result that a compartment 166 is produced therebeneath, which is conductively connected with the "ice" compartment by the plate 146. This compartment 166 is accessible through a door 167 mounted in the 45 wall of chamber 140 and is adapted for the reception of freezing pans 168 for the formation of ice cubes or use in freezing confections or for storing frozen products. The wall of the cabinet is preferably offset inwardly, as at 169, above the door openings, so that the body of the cabinet may be spaced from the front wall 170 of the chamber a sufficient distance to permit the provision of radiation vanes 147 between the cabinet and chamber walls thereabove. In this 50 illustration, where the apparatus is intended for household use and supplies of "ice" are readily available, necessity for a construction permitting more than one column of "ice", is eliminated and the entire supply may rest at its lower end directly upon the plate 146, or upon portable 55 insulation 160 as described above. The ice cube and frozen storage compartment 166 may, however, be conveniently combined with structures embodying several vertical columns of "ice" as 60 suggested in Fig. 30.

In Figs. 28 and 29, the construction of Figs. 25 to 27 is modified to permit its adaptation to a circular refrigerator having rotatable shelving units 171, the rotation of which will bring material stored therein opposite an access door 75

172, which door also is opposite, and gives access to the freezing chamber 166.

It will be noted that in each of the constructions illustrated, the principal heat transfer taking place between the refrigerating chamber and the "ice" in cabinet 144 is obtained through conduction, the conducting element being subject to the action of convection currents passing through the channels provided by the walls 148 and the cabinet. Thermostatic regulation of this passage materially reduces the speed by which the refrigerant is converted and enables the refrigerator to operate over a considerable period with a single filling. Since all gases resulting from reduction of the refrigerant are conducted to the exterior of the refrigerating chamber, they cannot come in contact with food or products stored therein to damage same in any way. By regulating and maintaining automatically the temperature in the storage chamber 140 either above or below 32° F. it is possible to refrigerate a large majority of products, particularly those perishable products that may be damaged by freezing, and thus the uses for this method of refrigeration are numerous. Because of the self-contained nature of the apparatus and its adaptation to small units it is especially useful for transportation purposes.

Figures 31 to 35 inclusive illustrate two kinds of storage boxes used for the preservation of perishable foods, for instance ice cream and other frozen foods, and are particularly adapted for the use of dry ice or brine ice. Fig. 31 is a vertical section of an ice cream cabinet using dry ice, in which 301 is the conventional insulated casing; 302 the storage compartment; 303 the metallic conductor formed preferably of a single sheet of copper or aluminum; 304 a mass of dry ice supported by that part of the conductor forming the bottom of the ice compartment; 305 is any preferred form of conductor resistance interposed between the ice and the conductor to regulate the temperature of the extended heat absorbing surfaces of the conductor and hence the temperature of the refrigerated space. For this type of cabinet the conductor is usually of $\frac{1}{4}$ " thick aluminum or $\frac{1}{3}$ " thick copper. It is more easily made if bent from a single continuous sheet, although the various extended areas can be welded together. In doing so, however, it is most important that the thickness of cross section is never decreased as the point of heat transfer with the ice is approached, as this would form a bottle neck through which the passage of heat would be restricted. Also it is preferable not to make any joints in the conductor except by welding. If two parts of a copper conductor were soldered together there would be a large drop in temperature across the joint because solder is a much poorer heat conductor than copper. In this form of metallic conductor installation it is preferable to have as large a proportion as possible of the total heat reaching the ice pass through the conductor all the way to the bottom of the ice compartment and there be transferred to the bottom surface of the ice by direct contact, or through the controlled conductor resistance 305.

Another advantage of the form of conductor shown in Fig. 1 is that because it is disposed around the inside walls of the storage compartment it absorbs a great deal of the heat coming in through the walls before it ever has an opportunity to reach the refrigerated goods; also being disposed mainly in the upper part of the refrigerated space the conductor tends to cut

down to a minimum the temperature differential between the top and bottom of the refrigerated space.

The large heat absorbing surfaces of the conductor as compared with the portion presented at the bottom of the ice compartment for transferring heat to the ice clearly is shown in Fig. 33.

Figs. 34 and 35 illustrate a cabinet similar to the combination shown in Fig. 31 and having the compartment, which in this particular form of the invention is adapted for dry ice, located in an upper corner of the space to be refrigerated. In these figures the reference character 306 indicates the cabinet having the ice compartment 307 located in the upper right-hand corner and the dry ice 308 is supported upon the conductor plate 309 which has a vertical plate-like extended portion 310 metallically joined to the edges thereof. The plate-like extended surface 310 has angular extensions 311 extending along opposite sides of the upper part of the compartment 312 for the material to be refrigerated.

This application is a continuation-in-part of my application for Method and apparatus for refrigeration, Serial No. 467,999, filed June 14, 1930, now Patent Number 2,055,158, which application in turn was filed as a continuation-in-part of my application for Method of refrigeration by means of solid carbon dioxide, Serial No. 372,754, filed June 21, 1929; and a continuation-in-part of my application Serial No. 751,391, for Refrigeration, filed November 3, 1934, which in turn is a division of my application Serial No. 679,435, filed July 7, 1933, for Refrigeration, now Patent No. 1,980,089.

I claim:

1. The method of refrigerating by means of a solid refrigerant which comprises maintaining a solid refrigerant in heat-conductive relation with a lower portion of a solid metallic heat conductor, having a thickness so correlated to the heat conductivity of the metal from which it is formed and the area of its surface exposed for heat absorption, that it is capable of transferring heat to the solid refrigerant at a rate sufficient to maintain the heat-absorbing surface thereof at an effective refrigerating temperature, absorbing heat from a space to be refrigerated by an upper portion of said conductor, and transferring the heat absorbed by the upper portion of the conductor downwardly through said conductor to the refrigerant at a rate sufficient to maintain an effective refrigerating temperature in said space.

2. In a refrigerating apparatus for use with solid refrigerants, means for absorbing heat taken up from the space or material to be cooled at a relatively high level and for transferring said heat downwardly to the solid refrigerant at a relatively low level, said means including a solid heat conductor having a portion exposed at the high level for heat absorption from the space or material to be cooled, and another portion to be maintained in continuous heat-conductive relation with the solid refrigerant at the lower level, the thickness of said conductor being so correlated to the heat conductivity of the metal from which it is formed and the area of its surface exposed for heat absorption as to maintain said heat-absorbing portion at an effective refrigerating temperature lower than that of the space or material to be cooled.

3. In a refrigerating apparatus for use with solid refrigerants, a refrigerant support comprising a generally horizontally disposed metallic heat conductor with which the solid refrigerant is to be maintained in heat-conductive relation and ex-

tended surfaces extending to a higher level for absorbing heat from the space to be cooled and conducting it downwardly to the portion of the conductor in contact with the solid refrigerant, 5 the thickness of said conductor being so correlated to the heat conductivity of the metal from which it is formed and the area of its surface exposed for heat absorption as to maintain said heat absorbing portions at an effective refrigerating 10 temperature lower than that of the space or material to be cooled.

4. In a refrigerating apparatus for use with solid refrigerants, a refrigerant support comprising a generally horizontally disposed metallic heat 15 conductor with which the solid refrigerant is to be maintained in heat-conductive relation and extended surfaces extending to a higher level for absorbing heat from the space to be cooled and conducting it downwardly to the portion of the 20 conductor in contact with the solid refrigerant, the thickness of said conductor being so correlated to the heat conductivity of the metal from which it is formed and the area of its surface exposed for heat absorption as to maintain said heat absorbing 25 portions at an effective refrigerating temperature lower than that of the space or material to be cooled, said extended heat-absorbing surfaces being in the form of a plate-like member metallically joined to the edge of the portion of the conductor upon which the refrigerant is supported.

5. In a refrigerating apparatus for use with solid refrigerants, a refrigerant support comprising a generally horizontally-disposed metallic heat conductor with which the solid refrigerant is to be 35 maintained in heat-conductive relation and extended surfaces including fins extending to a higher level for absorbing heat from the space to be cooled and conducting it downwardly to the portion of the conductor in contact with the solid refrigerant, the thickness of said conductor being 40 so correlated to the heat conductivity of the metal from which it is formed and the area of its surface exposed for heat absorption as to maintain said heat absorbing portions at an effective refrigerating 45 temperature lower than that of the space or material to be cooled.

6. In a refrigerating apparatus for use with solid refrigerants, a refrigerant support comprising a generally horizontally-disposed metallic heat conductor with which the solid refrigerant is to be 50 maintained in heat-conductive relation and extended surfaces extending to a higher level for absorbing heat from the space to be cooled and conducting it downwardly to the portion of the conductor in contact with the solid refrigerant, the thickness of said conductor being so correlated to the heat conductivity of the metal from which it is formed and the area of its surface exposed for heat absorption as to maintain said heat absorbing 55 portions at an effective refrigerating temperature lower than that of the space or material to be cooled, said extended surfaces at least partially inclosing the space or material to be cooled.

7. In a refrigerating apparatus adapted to be 65 cooled by a solid refrigerant and having a container for the refrigerant and a space to be cooled, a solid metallic heat conductor adjacent the bottom of the refrigerating container with which the solid refrigerant is to be maintained in heat-conductive 70 relation, said conductor having extended heat-absorbing portions at least partially surrounding the space to be refrigerated, said surrounding heat absorbing portions extending from an upper level downwardly to a level at least as 75 low as said conductor and being metallically

joined with the edges thereof, the thickness of said extended portions being so correlated to the heat conductivity of the metal from which they are formed and the area thereof exposed for heat absorption as to maintain said heat-absorbing portions at an effective refrigerating temperature lower than that of the space or material to be cooled. 5

8. In refrigerating apparatus, cooled by a solid refrigerant such as water ice, brine ice, or solid 10 carbon dioxide, a solid metallic heat conductor presenting surfaces for heat absorption from the refrigerated space or material of greater area than the surface of the conductor presented in the refrigerant containing space for heat transfer to 15 the refrigerant; the capacity of said conductor to transmit heat along in the direction of the refrigerant from the said surfaces presented for heat absorption being sufficient, by reason of its thickness or cross section, to maintain the said heat 20 absorbing surface areas at a lower temperature than that of the refrigerated space or material, said conductor consisting of a continuous thick metal plate extending in the refrigerated space from the refrigerant containing space, the said 25 heat-absorbing surfaces being formed by substantially vertical portions of said plate located in the upper part of the refrigerated space, which portions extend vertically from the bottom level of the refrigerant containing space and immediately 30 adjoin the said heat transferring surface located therein, the solid refrigerant being maintained gravitationally in continuous conductive relation with the said heat-transferring surface, which is 35 located above the bottom of the refrigerated space.

9. Refrigerating apparatus comprising a thermal conductor in the form of a container, an insulating casing for said container, said conductor having a thickness so correlated to the heat conductivity of the material from which it is formed, 40 and the area of its surface exposed for heat absorption as to be capable of maintaining in all parts of the contained space a substantially uniform refrigerating temperature by means of a solid refrigerant in conductive association with 45 that portion of the conductor forming the bottom of the container, and means in said container for supporting the material to be refrigerated above said refrigerant.

10. A refrigerating apparatus for use with a 50 solid refrigerant as the refrigerating medium, including an enclosed refrigerant-containing space or bunker, and a solid metallic heat conductor, a portion of which forms a wall of the refrigerant-containing space, with which portion the solid refrigerant is to be maintained in direct contact, and other portions of which are extended exteriorly of the refrigerated space or material, the said extended portions being formed by substantially flat sections of thick metal plate metallically 55 joined to one or more edges of, and extending for at least a portion of its length in substantially the same plane as that portion of the conductor with which the solid refrigerant is to be maintained in contact; the said conductor forming a direct, all-metallic, principal path of heat transfer between the refrigerated space or material and the refrigerant, the thickness of said extended portions being so correlated to the heat conductivity of the metal from which they are formed, and the area 60 of their surfaces exposed for heat absorption as to absorb a major amount of the heat to be transmitted by the said conductor.

11. In refrigerating apparatus for cooling by a solid refrigerant such as water ice, brine ice, or 70

solid carbon dioxide, a solid metallic heat conductor presenting extended surfaces for heat absorption from the space or material to be cooled of greater area than the surfaces of the conductor 5 presented in the refrigerant-containing space for direct contact and heat transfer with the refrigerant; the capacity of the said conductor to transmit heat along in the direction of the refrigerant from the said surfaces presented for heat absorption being sufficient, by reason of its thickness 10 with respect to the heat conductivity of the metal from which it is formed and the area of its extended surfaces exposed for heat absorption, to maintain the said heat-absorbing surface areas at an 15 effective refrigerating temperature lower than that of the space or material to be cooled, whereby the said heat-absorbing surfaces are adapted to absorb a major amount of the heat to be transmitted by said conductor; and the said extended 20 heat-absorbing surfaces being formed by substantially flat sections of metal plate metallically joined to one or more edges of, and extending for at least a portion of its length in substantially the same plane as that portion of the conductor with 25 which the solid refrigerant is to be maintained in contact.

12. In refrigerating apparatus for cooling by a solid refrigerant such as water ice, brine ice, or solid carbon dioxide, a solid metallic heat conductor presenting extended surfaces for heat absorption from the space or material to be cooled of greater area than the surfaces of the conductor presented in the refrigerant-containing space for direct contact and heat transfer with the refrigerant; the capacity of the said conductor to transmit heat along in the direction of the refrigerant from the said surfaces presented for heat absorption being sufficient, by reason of its thickness 30 with respect to the heat conductivity of the metal from which it is formed and the area of its extended surfaces exposed for heat absorption, to maintain the said heat-absorbing surface areas at an effective refrigerating temperature lower than that of the space or material to be cooled, whereby 35 the said heat-absorbing surfaces are adapted to absorb a major amount of the heat to be transmitted by said conductor; and the said extended heat-absorbing surfaces being formed by substantially flat sections of metal plate metallically joined to one or more edges of the remaining portions 40 of the conductor, and partially surrounding the refrigerated space.

13. In refrigerating apparatus for cooling by a solid refrigerant such as water ice, brine ice, or solid carbon dioxide, a solid metallic heat conductor presenting extended surfaces for heat absorption from the space or material to be cooled of greater area than the surfaces of the conductor presented in the refrigerant-containing space for 45 direct contact and heat transfer with the refrigerant; the capacity of the said conductor to transmit heat along in the direction of the refrigerant from the said surfaces presented for heat absorption being sufficient, by reason of its thickness with 50 respect to the heat conductivity of the metal from which it is formed and the area of its extended surfaces exposed for heat absorption, to maintain the said heat-absorbing surface areas at an effective refrigerating temperature lower than that of the space or material to be cooled, whereby the 55 said heat-absorbing surfaces are adapted to absorb a major amount of the heat to be transmitted by said conductor; and the said extended heat-absorbing surfaces being formed by substantially flat sections of metal plate metallically joined to 60

one or more edges of, and extending for at least a portion of its length in substantially the same plane as that portion of the conductor with which the solid refrigerant is to be maintained in contact, that portion of the conductor in contact with the refrigerant being located at or below the bottom level of the refrigerated space. 5

14. In refrigerating apparatus for cooling by a solid refrigerant such as water ice, brine ice, or solid carbon dioxide, a solid metallic heat conductor connecting the refrigerant-containing space and the space or material to be refrigerated, said conductor being formed by substantially flat sections of metal plate, a portion of which conductor is to be maintained in continuous conductive contact with the solid refrigerant, and other portions extending exteriorly of the refrigerant-containing space and adapted to absorb the major amount of heat taken up by the solid refrigerant from the refrigerated space or material, the said 20 latter portions being metallically joined to one or more edges of, and extending for at least a portion of its length in substantially the same plane as that portion of the conductor with which the solid refrigerant is to be maintained in contact, said 25 conductor having a thickness so correlated to the heat conductivity of the metal from which it is formed, and the area of its surface exposed for heat absorption as to transfer heat from the space to be refrigerated at a rate sufficient to maintain 30 an effective refrigerating temperature therein.

15. In refrigerating apparatus for cooling by a solid refrigerant such as water ice, brine ice, or solid carbon dioxide, a solid metallic heat conductor connecting the refrigerant-containing space and the space or material to be refrigerated, said conductor being formed by substantially flat sections of metal plate, a portion of which conductor is to be maintained in continuous conductive contact with the solid refrigerant, and other portions extending exteriorly of the refrigerant-containing space and adapted to absorb the major amount of heat taken up by the solid refrigerant from the refrigerated space or material, the said 35 latter portions being metallically joined to one or more edges of the said former portion, and partially surrounding the refrigerated space, the thickness of said conductor being so correlated to the heat conductivity of the metal from which it is formed, and the area of its surface exposed for 40 heat absorption as to transfer heat from said space at a rate sufficient to maintain an effective 45 refrigerating temperature. 50

16. In refrigerating apparatus for cooling by a solid refrigerant such as water ice, brine ice, or solid carbon dioxide, a solid metallic heat conductor connecting the refrigerant-containing space and the space or material to be refrigerated, said conductor being formed by substantially flat sections of metal plate, a portion of which conductor is to be maintained in continuous conductive contact with the solid refrigerant, and other portions of which absorb the major amount of heat taken up by the solid refrigerant from the refrigerated space or material, the said latter portions being metallically joined to one or more edges of, and extending for at least a portion of its length in substantially the same plane as that portion of the conductor with which the solid refrigerant is to be maintained in contact, and the said former portion being located at or below 60 the bottom level of the refrigerated space, the thickness of said conductor being so correlated to the heat conductivity of the metal from which it is formed, and the area of its surface exposed 65

70

75

for heat absorption as to transfer heat from said space at a rate sufficient to maintain an effective refrigerating temperature.

17. Refrigerating apparatus for use with solid carbon dioxide comprising a thermal conductor having a plurality of tubular extensions each forming a receptacle, an insulating housing entirely surrounding said conductor and said extensions, and means providing for operative association of said conductor with the said refrigerant, said conductor and the extensions thereof having a thickness so correlated to the heat conductivity of the material from which they are formed, and the area of surface exposed for heat absorption as to be capable of maintaining the entire space of each of said containers at a substantially uniform refrigerated temperature.

18. A refrigerating apparatus for use with a

solid refrigerant as the refrigerating medium comprising a refrigerant-containing space, a space to be refrigerated, and a solid metallic heat conductor forming the bottom of the refrigerant-containing space and adapted to be maintained in heat-conductive relation with refrigerant therein, said conductor having an extended portion forming the bottom of the space to be refrigerated, the thickness of the conductor and the extended portion being so correlated to the heat conductivity of the metal from which they are formed, and the area of the extended portion exposed for heat absorption in the space to be refrigerated being sufficient, that the conductor and the extended portion thereof form a direct, all-metallic path for transfer to the refrigerant of the major amount of heat absorbed from the space to be refrigerated.

EDWARD RICE, JR.
